UNITED STATES PATENT OFFICE.

CARL GUSTAV FISCHER, OF SCHLOSS HOLTE BRACKWEDE, NEAR BIELEFELD,
WESTPHALIA, GERMANY.

APPARATUS FOR SETTING TYPE.

SPECIFICATION forming part of Letters Patent No. 348,836, dated September 7, 1886.

Application filed July 10, 1885. Serial No. 171,213. (No model.) Patented in Germany September 14, 1884, No. 31,992, and in France January 24, 1885, No. 166,630.

To all whom it may concern:

Be it known that I, CARL GUSTAV FISCHER, engineer, a subject of the King of Prussia, and residing at Schloss Holte Brackwede, near 5 Bielefeld, Westphalia, Germany, have invented new and useful Improvements in Apparatuses for Facilitating the Setting of Type by Hand, (for which I have obtained Letters Patent in Germany, September 14, 1884, No. 31,992, and 10 France, January 24, 1885, No. 166,630,) of which the following is a specification.

My invention relates to apparatuses by means of which printing-types regularly stored up in a series of parallel cases are individually 15 pushed forward, so as to project from the cases and to be ready for being grasped and withdrawn by the compositor; and the improvements consist in the particular combination, with the type-cases, of type-ejectors worked 20 simultaneously by mechanism in the construction and mode of securing the type-cases, and in the arrangement of the ejectors in respect to each other.

On the annexed sheet of drawings, Figures 25 1 and 2 show, respectively, in rear and front elevation, an apparatus constructed according to my invention. Fig. 3 is a vertical transverse sectional view, and Fig. 4 a top view, partly in section. Fig. 5 shows in section and 30 full size two bars constituting the type-cases.

The apparatus consists substantially of the stationary type-cases *a*, *e*, arranged in a single row, and of the type-ejectors *t*, fixed to the standards *r*, secured to the bar *q*, which is 35 moved to and fro by mechanical means. The type-cases are formed by plates or bars *a*, having on one side at their longitudinal edges projecting flanges *e*. (See especially Fig. 5.) These bars are placed by the side of each other, so 40 that between them channels will be produced, each of which is adapted to receive a column of types, the types lying with their sides one upon the other. The flanges *e* are, however, only about half as high as the body of the 45 types, in consequence whereof slits will be left between the flanges *e* of one bar and the flat back of the neighboring bar. These slits allow the types to be seen, and through them a narrow instrument may be introduced for the

purpose of slowly lowering a column of types 50 when the case is to be filled, or for withdrawing types. On the side having the flanges *e* or inner side each bar *a* is provided at the proper height with a transverse piece, *h*, forming the bottom on which the column of types rests. 55 Immediately above this piece a portion of the front flange *e* is removed, and the opening thus produced is so far closed by a spring, *m*, that only the one type which is at the foot of the column can be pushed out at a time. On 60 these springs may be fixed plates showing the denomination of the types contained in the cases. Opposite to the opening for the issue of the type the back flange *e* has a notch for the passage of the ejector. The ejectors are 65 fixed in oblique rows to a number of small standards, *r*, and preferably upon steps of the same. These standards, of which, however, only one is shown in the drawings, are secured to a bar, *q*, guided in slots *p* of the two frame 70 parts *b* of the apparatus. The bar *q* is connected at its ends by means of pivots and bars *o* to eccentrics *n*, keyed on the shaft *k*, so that when this shaft is rotated the bar *q* will be put into transverse reciprocating motion, and 75 all the ejectors simultaneously moved backward and forward. The ejectors will consequently push forward at the same time all types which are in their original position at the bottom of a column, such of the ejectors as 80 are opposite to types already advanced moving to and fro in the spaces between the types next to the lowest ones and the bottom pieces, *h*. In any case, after each stroke of the ejectors, the lowest types of all columns will have 85 been pushed forward, so that the compositor may seize them. The shaft *k* may be rotated by any suitable means.

The system of arranging the ejectors and the corresponding portions of the type-cases 90 in oblique rows presents the advantage that the type-cases may be brought very close together, while the distance between the types projecting from the cases is sufficiently great that every type may be seized without inconvenience. Besides, the arrangement allows the points of issue of the types to be distributed alike to the boxes of the common type- 95

cases. The disposition of the type-cases in a single row presents, moreover, the advantage that the cases are easily accessible from both sides, and that they may be filled from the rear while the apparatus is working, and without hindrance to the compositor.

The bars *a* may be removably fixed in their position in various manners; but I prefer the following arrangement for this purpose. The bars are inserted with their foot, which is suitably recessed, into notches turned into the bar *d*, Figs. 2 and 3. They are thereby secured at this point against any lateral displacement. At the top they are suspended with a hook-shaped projection, *i*, on a ledge, *f*, of corresponding form, on the upper cross-bar, *e*, of the apparatus, and prevented from being accidentally lifted by pins *g*, extending through the bar *e* into the bars *a*. With this arrangement any one of the bars *a* may easily be taken out. In the drawings the said bars are shown as having a vertical position. They may, however, also be inclined backward or forward.

I claim as my invention—

1. In an apparatus for facilitating the setting of types by hand, the combination, with a plurality of stationary channel-like type-cases arranged in a row having the bottom pieces,

h, of the type-ejectors *l*, fixed in oblique rows to a reciprocating piece of machinery and adapted to simultaneously push forward the lowest types of all the type-columns which rest on the bottom pieces, *h*, arranged just below the path of the respective ejectors *l*, substantially as and for the purpose described. 35

2. In an apparatus comprising a row of stationary channel-like type-cases and a number of reciprocating type-ejectors operating as described, the type-cases consisting of bars *a*, having projecting flanges *e*, each case being 40 closed on one side by the back of the neighboring bar *a*, substantially as specified.

3. The combination, with the bars *a*, having projecting flanges *e* and a recessed foot, of the bar *d*, having grooves into which the bars *a* 45 are inserted with their recessed foot, and means, substantially as described, for fastening the bars *a* at the top, substantially as and for the purpose set forth.

In testimony whereof I have signed my 50 name to this specification in the presence of two subscribing witnesses.

CARL GUSTAV FISCHER.
